CLAIM

The ornamental design for an automobile front display, as shown and described.

DESCRIPTION

FIG. 1 is a front and right perspective view of an automobile front display, showing our new design;

FIG. 2 is a front elevation view thereof;

FIG. 3 is a right side elevation view thereof; and,

FIG. 4 is a top plan view thereof.

The claimed design is indicated by the relatively dark portions, while the relatively light and blurred portions form no part of the claimed design.
